CLAIM

The ornamental design for a support bracket, as shown and described.

DESCRIPTION

FIG. 1 is a front perspective view of the support bracket according to the present invention;

FIG. 2 is a rear perspective view of the support bracket according to the present invention as shown in FIG. 1;

FIG. 3 is a rear elevational view of the support bracket according to the present invention as shown in FIG. 1;

FIG. 4 is a front elevational view of the support bracket according to the present invention as shown in FIG. 1;

FIG. 5 is a right side view of the support bracket according to the present invention as shown in FIG. 1;

FIG. 6 is a left side view of the support bracket according to the present invention as shown in FIG. 1;

FIG. 7 is a top plan view of the support bracket according to the present invention as shown in FIG. 1; and,

FIG. 8 is a bottom plan view of the support bracket according to the present invention as shown in FIG. 1.

The broken lines illustrate portions of the article and form no part of the claimed design.
